CLAIM

The ornamental design for a display panel or screen with animated graphical user interface as shown and described.

DESCRIPTION

FIG. 1 is a front view of a display panel or screen with animated graphical user interface showing a first image of our new design;

FIG. 2 is a front view of a second image thereof;

FIG. 3 is a front view of a third image thereof; and,

FIG. 4 is a front view of a fourth image thereof.

The appearance of the animated image sequentially transitions between the images shown in FIG. 1 through FIG. 4. The process or period in which one image transitions to another forms no part of the claimed design. The broken lines depict portions of the display panel or screen with animated graphical user interface that form no part of the claimed design.
